UNITED STATES PATENT OFFICE.

WILLIAM L. HOOD, OF LEXINGTON, MASSACHUSETTS.

FLOUR AND SHORTENING BLENDER.

Application filed January 10, 1924. Serial No. 685,450.

The present invention relates to a device particularly designed for blending flour and shortening and which may be used to equal advantage for reducing fruit to a pulp, 5 mashing vegetables such as potatoes, and in a variety of ways for preparing food requiring the blending of two or more ingredients or the reducing of the same to a fine condition.

10 Other objects and advantages will be apparent and suggest themselves as the nature of the invention is understood.

While the drawings illustrate an embodiment of the invention it is to be understood 15 that in adapting the same to meet different conditions and requirements, various changes in the form, proportion and minor details of construction may be resorted to without departing from the spirit of the 20 invention.

Referring to the accompanying drawings forming a part of the application:

Figure 1 is a side view of an article of 25 the character aforesaid embodying the invention,

Figure 2 is an end view thereof, and

Figure 3 a horizontal section on the line 3—3 of Figure 1.

Corresponding and like parts are referred 30 to in the following description and designated in the several views of the drawings by like reference characters.

The device comprises a frame 1 which, as shown, is elongated and elliptical in outline, 35 although it is to be understood that the frame may be of any design, construction and size. Extensions 2 are located at opposite ends of the frame 1 and are disposed perpendicular thereto and support a handle 40 3.

In the preferable construction, the frame 1 and extensions 2 constitute parts of a stout wire, having end portions intertwined to provide the extensions 2 and having the intermediate portions outwardly curved or deflected to form the frame 1. The frame 45 preferably curves throughout its length so that a rocking movement may be imparted

thereto when the device is in active operation. A wire fabric 4 is stretched over the frame 1 and attached thereto. This fabric 50 is of coarse mesh and the wires or strands are relatively fine to constitute cutters, whereby to chop up the shortening and effect a blending thereof with the flour. The wires or strands comprising the fabric 4 are 55 crimped as at 5, intermediate the connection 6 between adjacent strands. These crimped portions 5 and connections 6 by giving the cuts made an irregular outline and also by providing for a slight vibration 60 of the fabric when in operation adds to the efficiency in the operation of the device in cutting up and granulating the shortening mixture, this being necessary and desirable for a satisfactory product. 65

When using the article to effect a blending of a shortening and flour, the handle 3 is grasped and the device moved through the mass of flour and shortening to produce a chopping and blending action, and the 70 reciprocating movement imparted to the device may be varied by rocking the same, provision being had for such movement by the curved outline of the frame 1. Manifestly, the uses of the article are many, as 75 herein indicated, while it is peculiarly adapted for the particular use herein stated.

What is claimed is:

A domestic utensil consisting of an elongated frame structure having side members 80 connected together at their opposite ends, members secured to and extending upwardly from the opposite ends of said side members, a handle member carried by the upper portions of said upwardly extended 85 members and disposed longitudinally of said frame member, and wire-like cutting members secured to and extending transversely across said frame structure and transversely 90 of said handle member.

In testimony whereof I affix my signature.

WILLIAM L. HOOD.
